INVENTOR
Frank Miller
BY
George C. Henricks
ATTORNEY

UNITED STATES PATENT OFFICE.

FRANK MILLER, OF WEST HOBOKEN, NEW JERSEY.

WALL-PAPER ROLLER.

Application filed November 2, 1922. Serial No. 598,640.

To all whom it may concern:

Be it known that I, FRANK MILLER, a citizen of Poland, residing at West Hoboken, county of Hudson, and State of New Jersey, 5 have invented certain new and useful Improvements in Wall-Paper Rollers, of which the following is a specification.

This invention relates to improvements in wall paper rollers used to smoothen the wall 10 paper after the same has been applied to the walls and ceiling of a room.

It is the principal object of my invention to provide a tool of this character which is simple and inexpensive in its construction, 15 yet durable and convenient to handle by a paperhanger.

Another object of the invention is the provision of a tool of this character which will not tear the paper, possessing enough 20 elasticity to yield when traveling over uneven spots in a wall or ceiling.

With these ends in view my novel tool consists in the novel construction, arrangement of parts and combination of elements 25 shown in the accompanying drawing, forming a material part of this disclosure, and in which:

Figure 1 is a front elevation of a tool constructed according to the present invention, and

Figure 2 is a side elevation of the same.

The tool comprises a handle 10 of suitable shape, length and material to the upper flattened part 11 of which a metal loop is 35 secured by means of headed bolts 12 passed through part 11 and the lower straight ends 13, 14 of the arms 15, 16 of the loop. In-

termidiate their ends, the arms 15, 16 are braced by means of a brace 17, the angular ends 18, 19 of which are secured to the inner 40 faces of arms 15, 16 by means of suitably headed bolts 20, 21. The upper ends of the arms 15, 16 are perforated to form bearings for the ends of a shaft 22 journaled therein which carries between arms 15, 16 a roller 45 23 covered with a corrugated rubber coating or cover 24.

It will be clear that a gentle pressure exerted by the roller 24 against the wall paper while the roller is traveling over the same, 50 will firmly press the paper against the wall and remove all wrinkles formed, without in any way injuring the same or its colors, while the arms 15, 16 will develop elasticity enough to avoid a tearing of the paper over 55 rough places in walls or ceilings.

Changes may be made in the general arrangement and the specific construction of the minor details of my device without deviating from the scope and spirit thereof. 60

What I claim is:

A tool as described comprising a handle, a loop formed by curved arms having straight lower ends adapted to engage said handle and to be secured thereto, the upper 65 ends of said arms perforated, a shaft journaled in the perforations of said upper ends, a roller on said shaft, a corrugated rubber covering for said roller, and a rod secured at each of its angular ends to said arms to 70 brace the same.

In testimony whereof I have affixed my signature.

FRANK MILLER.
